His Attorney.

UNITED STATES PATENT OFFICE.

FRED L. ANDERSON, OF KANSAS CITY, MISSOURI.

BURGLAR ALARM.

1,408,920.

Specification of Letters Patent. Patented Mar. 7, 1922.

Application filed May 12, 1919. Serial No. 296,526.

To all whom it may concern:

Be it known that I, FRED L. ANDERSON, a citizen of the United States, residing at Kansas City, in the county of Jackson and State of Missouri, have invented a certain new and useful Improvement in Burglar Alarms, of which the following is a specification.

My invention relates to improvements in burglar alarms.

My invention is particularly well adapted for use in the protection of banks, grocery stores, saloons, and similar places. It has lately been the custom for robbers to enter a bank, grocery store or saloon, hold up the proprietor or clerk, and then to lock him in the vault, or refrigerator, as the case may be.

The object of my invention is to provide novel means by which the person who is being held up can actuate with his foot and unobserved, a controlling device in circuit with an alarm or signalling device located at a distance.

My invention provides still further means by which the person, who is held up and has been locked in an enclosure, such as a vault or refrigerator, before he could actuate the signalling device, can actuate the alarm or signalling device from within the enclosure.

My invention provides still further means by which the person who has been locked in the vault or refrigerator, may cut out the circuit controlling device which is at the outside of the vault or refrigerator, to enable the person while in the enclosure to operate the signalling device independently of the outside circuit controlling device, so as to notify the police or public as to the number of the robbers, or to enable him to send some predetermined signal without interference from the controlling device which is located at the exterior of the enclosure in which he is locked.

The novel features of my invention are hereinafter fully described and claimed.

In the accompanying drawing which illustrates the preferred embodiment of my invention,

Fig. 1 is a view partly in side elevation and partly in vertical section of a bank building which is equipped with my improved burglar alarm.

Fig. 2 is an enlarged vertical sectional view of the circuit controlling device, such

as is employed inside and outside of the vault.

Fig. 3 is a diagrammatic view of the electrical circuit, which may be employed in connection with my invention.

Similar reference characters designate similar parts in the different views.

1 designates a building, such as a bank building, which is provided with a vault 2 having the usual door 3, adapted to be locked in the usual manner.

4 designates a counter located in a teller's cage 5, which communicates with the vault 2 through the doorway of the latter.

At any desired place, preferably at a substantial distance from the building 1, is located one or more signalling devices, such as an electro-magnetic gong or bell 6 and an electro-magnetic siren 7.

Connected to the gong 6 and siren 7, which may be mounted on a post 8, is a suitable conduit 9, which, preferably, extends under the building 1 and into the vault 2.

Any suitable circuit controlling devices may be provided, one in the vault 2 and one preferably in the floor under the counter 4.

In the drawing I have illustrated the circuit controlling devices used in the vault 2 and under the counter 4, as push buttons, 85 each comprising a casing 10 containing two spring contact plates 11 and 12 insulated from each other and normally holding between them a slideable stem 13 having on its end a block of insulation 14, which separates electrically the contact plates 11 and 12. Each stem has a peripheral groove 15 adapted to receive the free ends of the plates 11 and 12 so as to be held by said plates in the closed position, after the stem 13 has been manually depressed.

On the casing 10 of the push button located in the vault 2 is a switch lever 16 by which a person in the vault may render inoperative the push button located under the counter 4.

Referring to Fig. 3, 17 designates a battery one pole of which is connected by a conductor 18 with one terminal of the electro-magnetic siren 7 of any suitable type, the other terminal of which is connected by a conductor 19 with one terminal of the electro-magnetic bell or gong 6, the other terminal of which is connected by a conductor 20 with the spring contact plate 11 of the push button which is in the vault 2, the other terminal of which is connected by a

conductor 21 which is connected to the other pole of the battery 17.

The conductor 20 is connected by a conductor 22 with the contact plate 11, of the 5 push button which is under the counter 4, the other contact plate 12 of which is connected by a conductor 23, which includes switch lever 16, with the conductor 21.

In the operation of my invention, when 10 the person in the cage 5 is held up by robbers, he may depress the stem 13 of the push button which is under the counter 4, by pressing downwardly on the same with his foot, so as to bring the adjacent contact 15 plates 11 and 12 into the groove 15 of the push button. The current will then pass from the battery 17 through conductor 18, siren 7, conductor 19, gong 6, conductor 20, conductor 22, contact plate 11 connected 20 therewith, adjacent stem 13, contact plate 20 12, conductor 20, switch lever 16 (which is normally closed), and conductor 20 back to the battery 17. The siren 7 and gong 6 will thus be actuated and will continue to 25 give an alarm until the depressed stem 13 of the push button under the counter 4 has been manually withdrawn to the open position shown, in which position the contact plates 11 and 12 rest upon the insulation 14.

If now the person in the cage 5 is locked 30 in the vault 2, and he has failed to depress the push button stem of the push button under the counter 4, he can, nevertheless, give an alarm by depressing the stem 13 of 35 the push button which is in the vault 2. When this has been done, the current will pass from the battery, as before described, through the siren 7 and gong 6 and conductor 20, and from thence through the conductor 40 20 contact plate 11 of the push button which is in the vault 2, thence through the adjacent stem 13, contact plate 12 and conductor 21 back to the battery.

It may be that the person in the vault will 45 desire to sound on the alarm some preconcerted signal indicating the number of the robbers. This he can do by rendering inoperative the push button under the counter 4,

which can be effected by throwing the switch lever 16 to the open position, thus disconnecting the push button under the counter 4 from the conductor 21. He can now open and close the push button in the vault the 50 number of times required to designate the number of robbers, or in such manner as to 55 utilize the Morse code for sending such signal or message as he may wish.

By pulling out the push button stems 13, the apparatus is restored to its original condition ready for another alarm to be sent. 60

From the foregoing it will be understood 65 that a person who is being held up in a bank, store, saloon or other similar place, may unobserved send in an alarm before he is locked in the vault or refrigerator. Or, in case that 70 he is unable to send in the alarm before being imprisoned in the vault or refrigerator, he can from the vault or refrigerator send in an alarm of any desired nature. In case that he has already sent in a general alarm 75 by means of the push button under the counter 4, he can by cutting out such push button, by moving the lever 16 to the open position, send preconcerted signals conveying such information as he may desire to send, 80 and without the knowledge of the robbers 85 by whom he has been held up.

I do not limit my invention to the structure shown and described, as modifications, 90 within the scope of the appended claim, may 80 be made without departing from the spirit of my invention.

What I claim is:—

In a burglar alarm system, an enclosure, 95 a signal, and a circuit for said signal comprising a circuit closer outside of said enclosure, a manually operated switch inside said enclosure in series with said circuit closer to render it operative or inoperative, and a circuit closer inside said enclosure in 100 parallel with said switch and said first named circuit closer, substantially as set forth.

In testimony whereof I have signed my name to this specification.

FRED L. ANDERSON.
